UNITED STATES PATENT OFFICE.

FRANK H. BROWN AND JOHN E. HANRAHAN, OF BALTIMORE, AND GEORGE A. BOYDEN, OF MOUNT WASHINGTON, MARYLAND, ASSIGNORS TO NATIONAL COMPOSITE TYPE COMPANY, A CORPORATION OF DELAWARE.

MOLD FOR CASTING TYPE, SPACES, AND QUADS.

No. 852,162.

Specification of Letters Patent.

Patented April 30, 1907.

Application filed May 19, 1905. Renewed February 8, 1907. Serial No. 356,340.

To all whom it may concern:

Be it known that we, FRANK H. BROWN and JOHN E. HANRAHAN, of the city of Baltimore and State of Maryland, and GEORGE A. BOYDEN, of Mount Washington, in the county of Baltimore, State of Maryland, citizens of the United States, have invented certain new and useful Improvements in Molds for Casting Type, Spaces, and Quads, of which the following is a specification.

This invention relates to a mold mechanism for casting type bodies, spaces and quads.

It is a well known fact to those skilled in the art of making type that those type-bodies which are provided with a character should be longer than the space or quads which are not provided with characters and which are employed in separating words of a sentence, or one sentence from another.

The present invention has among its objects to provide an improved mold in which the types of different lengths—those with characters, as well as the shorter spaces or quads, may both be cast.

The broad idea therefore of the present invention is to combine with a type mold, devices or instrumentalities which by entering the mold cavity in a lengthwise or heightwise direction will shorten the cavity so that bodies of different lengths may be cast in the same mold.

With these objects therefore in view the accompanying drawing illustrates one form of device for carrying the invention into practical effect without however in any way limiting the invention to the particular devices shown.

Figure 1 illustrates a sectional plan view of the mold parts and ejectors in the operative position. Fig. 2 illustrates a vertical section through the mold parts and matrix and shows the lengthwise reduction in the mold cavity for the purpose of casting spaces or quads. Fig. 3 illustrates a side elevation of a matrix employed in casting the shorter spaces or quads, and Fig. 4 illustrates an edge view of same.

In the drawing, 1, designates the base block of the mold, the top surface of which in the present instance is provided with a longitudinally-extending bead, 2. A plate, 3, has position at one side of the base block and serves

as a lower guide on which a gate or jet ejector, 4, may slide. A plate, 5, in the present instance has position above the guide plate 3 and serves as an upper guide for the ejector 4. A nipple-plate, 6, has position at the side of the guide-plates 3 and 5 and said nipple-plate is provided with a port, 7. It is also to be understood that any preferred form of metal supply device may be employed in connection with the invention and that the molten metal will be supplied through the port, 7.

An ejector, 8, has position on the top surface of the base-block 1 and the ends of said ejector, in the present instance, are designed to form one side wall of the mold cavity as will hereinafter be more fully described. The ejector 8 is provided at each end with a perforation 9, and the opposite flat longitudinal sides or surfaces of the ejectors are each provided with a groove, 10, which extend from the ends toward the center. The groove at one end of the ejector being on the opposite side from the groove at the other end. These grooves fit, one at a time, over the bead 2 on the base block 1. At end of the ejector 8 the side is provided with a notch, 11, which reduces the width so that the ejector is narrower at one end than at the opposite end. By this construction and arrangement of ejector the latter may be reversed so that when it is desired to cast bodies of the standard type-high size the wider end of the ejector may be employed to serve as one of the walls of the mold cavity and when it is desired to cast bodies either with or without characters, such for example as quads and spaces or short type with characters, the ejector may be reversed so that the narrower end may serve as one of the walls of the mold cavity.

The parts thus far described and in the present instance are arranged with respect to each other to form two right angles sides 95 and one end of the mold cavity, the base block forming one side, the end of the ejector forming a side at right angles to the base block and the guide plates 3 and 5 serving to close the cavity at the end when the molten metal is injected. The parts to coact with those heretofore described to form the other two sides and end of the mold cavity will now be described, it being understood that

the same are susceptible of being formed in a variety of ways and that the drawings are merely illustrative of one particular form of device.

- 5 A mold block, 12, is provided with a side plate, 13, which overlaps the ends of the guide and nipple plates, 3, 5 and 6, when the parts all come together and this mold block is also provided with right-angled surfaces, 10, 15, and, 16, which with the end of the ejector 8 and the base block, 1, when the parts are together, complete the four side walls of the mold cavity, 17. The mold block 12 is also provided with a vertically-extending recess, 15, 18, at one end of the mold cavity and a matrix, 19, fits in a holder, 20, in said vertical recess and forms the other end wall, 21, of the mold cavity.

The broad idea of the present invention is produced by bringing together a combination of devices or instrumentalities by means of which the lengths of the mold cavity may be varied so as to cast types of longer or shorter lengths. In the operation of the devices described this variation in the length or height of the bodies is embodied as follows: When it is desired to cast spaces or quads or bodies of a shorter length than the standard, the ejector 8 will be reversed so that the narrower end will have position adjacent the mold block 12 as seen in Fig. 1, and the matrix shown in Figs. 3 and 4 with a projecting surface, 22, will be inserted in the holder, 20, and the two then placed in the mold-block recess 18 so that when the mold parts are brought together as seen in Fig. 2, the said cameo or projecting surface 22 on the matrix will extend into the mold cavity 17 and thus reduce the length of said cavity. 40 The body then produced will be of a shorter length than the standard. It will thus be seen that the longer the projection on the matrix the shorter will the mold cavity become when the matrix and mold are in the operative condition.

The inventive idea here involved may find

expression in various mechanical forms, and we have, for the purpose of illustrating the invention, shown one of such forms in the accompanying drawing; but it is to be distinctly understood that said drawings are intended for the purpose of illustration only and not as in any way defining the limits or scope of the invention.

Having thus described our invention what we claim as new and desire to secure by Letters Patent is,

1. A type mold provided with a cavity, and a matrix movable in a direction parallel with the length of the cavity and having a projection to enter said cavity at the end to reduce its length.

2. A type mold comprising a stationary section and a section movable at right angles to the stationary section whereby to form a cavity between said sections, and a matrix carried by one of said sections and having a projection which enters the cavity to reduce its length.

3. A mold for casting type bodies comprising the mold sections; an ejector coacting with the mold sections to form the mold cavity, and a matrix having a projection which enters one end of said mold cavity to reduce the size of said cavity in a lengthwise direction.

4. A mold in which metal type bodies are to be cast provided with a cavity; an ejector having one end which is wider than the other in a direction lengthwise with respect to the mold cavity and said ejector capable of reversal end for end, and matrices arranged to coact with the ends of said ejector whereby type bodies of different heights may be cast.

In testimony whereof we affix our signatures in presence of two witnesses.

FRANK H. BROWN.
JOHN E. HANRAHAN.
GEORGE A. BOYDEN.
